UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,347,747.

Specification of Letters Patent.

Patented July 27, 1920.

Application filed August 23, 1917, Serial No. 187,730. Renewed January 27, 1920. Serial No. 354,513.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler No. 436,532, wherein circulating 15 matrices, by the manipulation of a keyboard, are released from a channeled magazine in the order in which their characters are to appear in print and then assembled in line, the composed line transferred to 20 the face of a mold, the mold filled with molten metal to form a slug or linotype against the matrices which produce the type characters thereon, and the matrices thereafter returned through a distributing mechanism to the magazine from which they 25 started.

The keyboard ordinarily employed in these machines comprises as many finger keys as there are characters in a matrix 30 font, each key being connected to and located substantially in the vertical plane of the particular magazine channel containing matrices of the corresponding character, and the keyboard is of practically the same 35 width as that of the discharge end of the magazine and has its finger keys disposed in the same order in which the matrix columns are arranged in the magazine channels. In short, the keyboard is of a construction 40 peculiar to the linotype machine and differs radically from the standard or universal keyboard used in other machines, such as typewriters and the like. The result is that there are now two distinct classes of 45 machine operators, one class familiar only with the linotype, and the other only with the typewriter.

It is the aim of my invention to eliminate this class distinction and to make it possible for an operator skilled in the manipulation of one kind of machine to turn readily to the other and to operate it with the same ease and facility. To this end, specifically, I propose to equip the linotype machine with a keyboard corresponding in size and

in number and arrangement of its finger keys with the standard typewriter keyboard and embodying a shift key to change from small to capital letters, etc., as in the case of the typewriter. In making use of this new keyboard, the channels of the magazine (which itself is of ordinary construction) are divided into groups, those of one group containing the small letters, the numbers and miscellaneous characters, and those of the other group containing the capital letters and extra characters, and mechanism is provided whereby the keyboard may be connected to either group of magazine channels at will, the parts being arranged in such manner that normally the keyboard is connected to the group containing the small letters, etc., and then connected to the group containing the capital letters, etc., upon the depression of the shift key.

While my invention has in view the special object mentioned, it is obviously capable of far wider application, it being useful in any case where it is desired to connect the keyboard as a whole to different groups of magazine channels, whether such keyboard be of the typewriter variety or otherwise. These and other features will more fully appear in the detailed description to follow.

In the accompanying drawings, I have shown my improvements merely in preferred form and by way of example and as applied to a machine of the kind noted, it being a desideratum to make as little change 90 as possible in the present organization of the machine or in the parts thereof which are generally of standard construction. It will be obvious, however, that my improvements may be embodied in other forms and 95 applied to machines of other constructions without departing from the spirit of my invention.

Generally speaking, I desire it to be understood that I do not limit myself to 100 any specific form or embodiment, except in so far as such limitations are specified in the claims.

Referring to the drawings:

Figure 1 is a diagram of my improved 105 construction, showing the keyboard, matrices and magazine, and the intermediate connections, etc.;

Fig. 2 is a vertical section through the keyboard and the operating devices; 110

Fig. 3 is a front view of a portion of the operating devices shown in Fig. 2;

Fig. 4 is a section on the line 4—4 of Fig. 3;

5 Fig. 5 is a side view of the keyboard showing the shift key and its connections to the other parts; and

Fig. 6 is a detail section taken on the line 6—6 of Fig. 5.

10 As customary, the matrices X of a given font are stored according to character in the grooved channels of the magazine A, and are released therefrom by the series of escapements B, one for each channel. The 15 escapements are actuated by the corresponding series of vertical reeds C, which in turn are operated, through intermediate connections subsequently to be described, by the pivoted yokes D. These yokes, as usual, are 20 arranged in staggered banks and are provided with the cams or eccentrics D¹ to co-operate with the underlying power-driven rolls D² under the control of the dogs or triggers D³. The dogs D³ are connected to 25 the upper ends of the vertical slides D⁴, which at their lower ends are connected to the finger keys E¹ of the keyboard E, there being as many cam yokes D and controlling slides D⁴ as there are finger keys in the keyboard.

30 In accordance with my invention, the number of finger keys E¹ employed is the same as that comprised in the standard typewriter keyboard, viz., forty-two, and 35 they are arranged in like order as to their characters, two of which are represented by each key, as customary. The keyboard E, therefore, is not only much smaller than the regular linotype keyboard, but differs further therefrom in respect to the number of 40 keys and their order of arrangement, it being understood that the linotype keyboard is as wide as the discharge end of the magazine, since it comprises as many finger keys 45 as there are characters in the matrix font, and has its finger keys arranged in the same order in which the matrices are stored in the magazine channels. These differences will be apparent from the diagram of Fig. 50 1, wherein the parts have been lettered as above. As therein shown, the keyboard is much narrower than the discharge end of the magazine, which is of normal size and contains twice as many matrix channels as 55 there are finger keys in the keyboard. The matrices are arranged in the magazine according to character in a different order than that of the finger keys, this difference being due to the fact that the matrices are 60 stored in their regular order (as indicated by the letters at the top of the figure), while the finger keys are arranged in the order in which they would appear in a typewriter keyboard.

65 In making use of the above keyboard, and

as a further step in carrying out my invention, I divide the magazine channels into groups and store the matrices bearing the small letters, the numbers and miscellaneous characters (which may be regarded as 70 "lower case matrices") in the channels of one group, and the matrices bearing the capital letters and the extra characters (which may be regarded as "upper case matrices") in the channels of the other 75 group; and I propose to connect the keyboard as a whole to either of these two groups, each one of which contains as many different matrix characters as there are finger keys in the keyboard. Such connection is effected by mechanism under the control of a shift key, as will now be described, attention being directed to the fact that the mechanism is designed to provide for the difference in width between the keyboard 80 and the magazine and also for the difference in the order of arrangement of the matrices in the magazine and the finger keys in the keyboard.

The escapements B and their actuating 90 reeds C are divided into groups corresponding to the group arrangement of the magazine channels, and they are adapted to be operated by a single or common group of rods or sections G slidably supported in 95 guide or comb plates G¹ and G² above the cam yokes D. The operating movement of the rods G is communicated to the escapement reeds C through the medium of U-shaped bails or frames F pivotally mounted 100 in superposed relation upon transverse rods F¹ of a box-like supporting structure F², enclosing the bails and which is detachably connected to the framework, so that all of the parts may be applied to or removed 105 from the machine as a unit. The bails F are arranged in sets, those of each set having their inner arms disposed side by side above the operating rods G and extending laterally therefrom to present their outer 110 arms (arranged) in engagement with the lower ends of the corresponding escapement reeds C of the two groups. Thus, in Fig. 3 the two uppermost bails are shown with their outer arms in engagement with the 115 reeds C controlling the release of the upper and lower case matrices bearing the letter e, which reeds are non-contiguous and remote from each other, and with their inner arms lying side by side above that operating rod G which is controlled by the finger key bearing the same letter. The bails for each of the other pairs of escapement rods are arranged in similar manner, it being understood that the bails differ in width 120 according to the distance between the escapement reeds and the common operating 125 rod.

With the parts thus arranged, the operating rods G may be connected with either 130

set of bails F by a slight lateral displacement at their upper ends, as indicated by the dotted lines in Fig. 3. This displacement of the rods is effected by their upper comb 5 plate G¹ which is slidably mounted in the framework so as to be shiftable longitudinally in opposite directions to locate the rods beneath the inner arms of first one set of bails and then the other. The plate G¹ 10 is so shifted by means of an upright lever H pivoted between its ends to the framework and formed at its lower end with an inclined or cam slot H¹ (Fig. 6), wherein engages a pin H² projecting rearwardly 15 from a pivoted shift key H³ arranged at one side of the keyboard (Fig. 5). Attached to the shift key H³ back of its pivot is a spring H⁴ tending constantly to maintain it in its raised position and with its lower end de- 20 pressed. In such position of the key, which is the normal one, its pin H² engages in the lower portion of the slot H¹ of the lever H, which consequently holds the plate G¹ in its position to the right, with the rods G in op- 25 erative relation to the set of bails leading to the escapement reeds C for the lower case matrices. When, however, the shift key is depressed against the action of its spring (see dotted lines of Figs. 5 and 6) its pro- 30 jecting pin H² is moved into the upper portion of the cam slot H¹, causing the lever H to shift the bar G¹ to the left to bring the rods G beneath or in engaging relation to the set of bails leading to the escapement 35 reeds for the upper case matrices. In this way the operator may change back and forth between upper and lower case matrices at will, the keyboard being normally connected to the magazine channels containing 40 the lower case matrices, and then connected to the channels for the upper case matrices upon the mere depression of the shift key.

As is well known, the linotype machine is also equipped with a separate magazine containing expandible or justifying space bands which are assembled in line between word groups of matrices. In the present instance, the delivery of these space bands is controlled by means of a key or bar E² which 45 is arranged in the keyboard in a position corresponding to that of the usual space key of the typewriter. This space band key, like the other finger keys, is connected at its rear end (Fig. 1) to an extra slide D⁴ con- 50 trolling the operation of a further cam yoke D, which latter is connected in the usual way (not shown) to the escapement of the space band magazine.

The general arrangement of the parts is 55 illustrated in the diagram of Fig. 1, from which it will be easy to trace the connections from various keys to the magazine or the matrices which they control. In view of the foregoing description no further explanation is necessary, except possibly to point

out that some of the bails F are omitted in the diagram for the sake of clearness, although enough of them appear to illustrate the principle of operation fully. It may also be noted that the upper case matrices 70 for the most part are stored in the right half of the magazine, while the lower case matrices are stored in the left half, this being entirely true of the small and capital letters, but otherwise as to the numbers and 75 the other miscellaneous characters, such, for instance, as 2-em, 3-en, 4-th, etc. This particular grouping of the matrices has been followed, as above stated, to preserve their regular order of arrangement in the maga- 80 zine channels, and it is evident that the grouping might be otherwise if desired.

As previously stated, I have shown my invention only in preferred form and by way of example, and obviously many modifications and alterations therein, and in its mode of adaptation, will suggest themselves to those skilled in the art, and will still be comprised within its scope.

Having thus described my invention, its 90 construction and mode of operation, what I claim and desire to secure by Letters-Patent of the United States is:

1. In a typographical machine, the combination of a channeled magazine containing a font or set of matrices divided into groups, a bank of escapements controlling the release of the matrices from the magazine, a series of escapement actuating reeds divided into groups corresponding to the 95 group arrangement of the matrices in the magazine, the corresponding reeds in the respective groups being located remotely from each other, a keyboard, and mechanical devices whereby the keyboard as a whole may 100 be connected to one or another of the groups of escapement actuating reeds to effect the release of matrices of the corresponding group from the magazine.

2. In a typographical machine, the combination of a channeled magazine containing a font of matrices arranged therein in a given order as to character, a keyboard having its finger keys arranged in a different order as to character, and mechanical 110 devices whereby the keyboard as a whole may be connected to different groups of 115 magazine channels to select one portion or another of the matrix font.

3. A structure as specified in claim 1, 120 characterized by the fact that at its discharge end the magazine is of materially greater width than that of the keyboard.

4. A structure as specified in claim 1, 125 characterized by the fact that the keyboard corresponds in size and in number and arrangement of its finger keys with the standard typewriter keyboard.

5. A structure as specified in claim 1, 130 characterized by the fact that the magazine

is of usual construction and has its contained matrices arranged in the regular order, and the further fact that the keyboard corresponds in size and in the number and arrangement of its finger keys with the standard typewriter keyboard.

6. A structure as specified in claim 1, characterized by the fact that one of the groups of magazine channels contains lower case matrices and the other group upper case matrices.

7. A structure as specified in claim 1, in combination with a shift key to control the connection of the keyboard with the different groups of escapement actuating reeds.

8. A structure as specified in claim 1, and wherein the keyboard is normally connected with one of the groups of escapement actuating reeds, in combination with a shift key 20 to effect its connection with another group of escapement actuating reeds at will.

9. In a typographical machine, the combination of a channeled matrix magazine having escapements, a series of escapement actuating reeds, divided into groups, the corresponding reeds in the respective groups being located remotely from each other, a keyboard, and intermediate mechanism for connecting the keyboard as a whole to one 25 or another of the groups of escapement actuating reeds so that the same key may actuate non-contiguous and remote reeds in the respective groups.

10. In a typographical machine, the combination of a channeled matrix magazine having escapements, a series of escapement actuating reeds divided into groups, the corresponding reeds in the respective groups being located remotely from each other, a 30 single group of key-controlled operating rods or sections, and means for connecting the operating rods to any selected group of escapement actuating reeds so that the same rod may actuate non-contiguous and remote 35 reeds in the respective groups.

45 11. In a typographical machine, the combination of a channeled matrix magazine having escapements, a series of escapement actuating reeds divided into groups, the corresponding reeds in the respective groups being located remotely from each other, a single group of key-controlled operating rods or sections, connecting bails arranged 50 between the operating rods and the escapement actuating reeds and divided into sets, one for each group of reeds, and means for connecting the operating rods to any selected 55 set of bails so that the same rod may actuate

non-contiguous and remote reeds in the respective groups.

60 12. In a typographical machine, the combination of a channeled matrix magazine having escapements, a series of escapement actuating reeds divided into groups, a single group of key-controlled operating rods or 65 sections, sets of intermediate connecting bails engaged at one end with the escapement reeds of the respective groups and having their opposite ends disposed side by side adjacent the group of operating rods, 70 and means for shifting the operating rods laterally into engaging relation to any selected set of bails.

75 13. A structure as specified in claim 10, in combination with a shift key to control the connection of the operating rods with the desired group of escapement actuating reeds.

80 14. A structure as specified in claim 10, characterized by the fact that the key-controlled operating rods are power-actuated.

85 15. A structure as specified in claim 11, characterized by the fact that the intermediate connecting bails are mounted in a supporting structure which is detachably connected to the framework of the machine so that the parts may be applied to or removed therefrom as a unit.

90 16. In a typographical machine, the combination of a matrix magazine, a bank of escapements controlling the release of the matrices therefrom, a series of escapement actuating reeds, a keyboard having finger keys each removed laterally from the escapement actuating reed it controls, and intermediate laterally offset devices through 95 which the respective finger keys operate the escapement actuating reeds.

100 17. In a typographical machine, the combination of a matrix magazine, a bank of escapements controlling the release of the matrices therefrom, a series of escapement actuating reeds divided into groups, a keyboard having finger keys each controlling the operation of the corresponding actuating reeds of said groups and removed laterally 105 therefrom, and intermediate offset devices through which the respective finger keys operate the escapement actuating reeds of any selected group.

110 In testimony whereof I have affixed my signature in presence of two witnesses.

DAVID S. KENNEDY.
